CLAIM

The ornamental design for a vibratory device for use on a pair of hanging ropes of an exercise apparatus, according to the invention, as shown and described.

DESCRIPTION

FIG. 1 is a front perspective view from above and one side of the vibratory device for use on a pair of hanging ropes of an exercise apparatus, showing my new design;

FIG. 2 is a rear perspective view from below and the other side;

FIG. 3 is a front elevation view thereof;

FIG. 4 is a rear elevation view thereof;

FIG. 5 is a top plan view thereof;

FIG. 6 is a bottom plan view thereof;

FIG. 7 is a right side elevation view thereof; and,

FIG. 8 is a left side elevation view thereof.
